CLAIM

The ornamental design for an auto-darkening welding filter display screen with touch graphical user interface, as shown and described.

DESCRIPTION

FIG. 1 is a top, back, right side perspective view of a first embodiment of an auto-darkening welding filter display screen with touch graphical user interface showing my new design;

FIG. 2 is a top, front, right side perspective view thereof;

FIG. 3 is a rear view thereof;

FIG. 4 is a front view thereof;

FIG. 5 is a left side view thereof;

FIG. 6 is a right side view thereof;

FIG. 7 is a top plan view thereof; and

FIG. 8 is a bottom plan view thereof.

FIG. 9 is an enlarged front view of a second embodiment of an auto-darkening welding filter display screen with touch graphical user interface, showing my new design; and, FIG. 10 is an enlarged front view of a third embodiment of an auto-darkening welding filter display screen with touch graphical user interface, showing my new design.

In the drawings, the dash-dash broken lines are for the purpose of illustrating the auto-darkening welding filter display screen with touch graphical user interface that forms no part of the claimed design. In FIGS. 1, 3, 9, and 10 the fragmented lines form a part of the claimed design.

1 Claim, 9 Drawing Sheets
